CLAIM

The ornamental design for a vehicle mirror, as shown and described.

DESCRIPTION

FIG. 1 is a front and left perspective view of a vehicle mirror showing our new design; the mirror image of the vehicle mirror is claimed, but not shown;

FIG. 2 is a front elevation view of the vehicle mirror of FIG. 1;

FIG. 3 is a left elevation view thereof; and,

FIG. 4 is a top view thereof.

The broken lines in the drawings depict portions of the vehicle mirror that form no part of the claimed design.
